UNITED STATES PATENT OFFICE.

THOMAS J. STEARNS, OF BOSTON, MASSACHUSETTS, ASSIGNOR TO THE ROXBURY CARPET COMPANY, OF SAME PLACE.

DESIGN FOR CARPETS.

SPECIFICATION forming part of Design No. 11,647, dated February 10, 1880.

Application filed December 23, 1879. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration. It consists of four independent bouquets or sprays, A B C D, each differing in form from the others. The bouquets are arranged in irregular diagonal rows, each of which is composed of two of the bouquets repeatedly alternating with each other, the next row being composed of the other two bouquets repeatedly alternating with each other.

In the design Patent No. 9,708, issued to me January 16, 1877, independent bouquets are shown forming diagonal rows; but the

whole design is composed of two bouquets repeatedly alternating in each row, and each row is a duplicate of the next. My present design therefore presents a greater variety of floral designs than the design shown in said patent.

I claim—

The design for a carpet, consisting of the four independent bouquets or sprays, each differing from the others, and all arranged as shown and described.

In testimony whereof I have signed my name to this specification, in the presence of two subscribing witnesses, this 16th day of December, 1879.

THOMAS J. STEARNS.
